UNITED STATES PATENT OFFICE.

CHARLES WHITTIER, OF BOSTON, MASSACHUSETTS.

ELEVATOR MECHANISM.

SPECIFICATION forming part of Letters Patent No. 421,150, dated February 11, 1890.

Application filed August 9, 1889. Serial No. 320,222. (No model.)

To all whom it may concern:

Be it known that I, CHARLES WHITTIER, of Boston, county of Suffolk, State of Massachusetts, have invented an Improvement in 5 Elevator Mechanism, of which the following description, in connection with the accompanying drawings, is a specification, like letters on the drawings representing like parts.

This invention relates to hydraulic elevators, and has for its object to improve the construction and operation of the same.

One feature of my present invention consists in locating within the cylinder containing the piston for actuating the elevator-car 15 a stand-pipe performing the double office of an inlet and outlet pipe for the water used to elevate the car, whereby the said pipe is removed from danger of being injured or deranged, and the objectionable noise caused 20 by the water passing through the said pipe is substantially obviated, the said stand-pipe enabling the apparatus to be made more compact than heretofore.

Another feature of my invention consists 25 in providing the cylinder referred to with an independent base, to which may be detachably secured a valve-casing containing the valve for controlling the admission of water to the cylinder. The base referred to is preferably provided with supports or legs, and 30 the valve-casing is secured to the under side of the said base and is readily accessible for purpose of repairs or cleansing, the said legs or supports enabling the said base to be 35 turned in any direction and yet present an open space, for a purpose to be described. The valve-casing referred to is preferably made independent of the base, so that the 40 said valve-casing may be turned into any desired position before being permanently secured to the base to enable the apparatus to be set up in irregular and limited spaces and at the same time secure perfect alignment of the valve mechanism and the hoisting-ropes.

45 The particular features in which my invention consists will be pointed out in the claims at the end of this specification.

Figure 1, in section and elevation, shows a sufficient portion of a hydraulic-elevator apparatus embodying my invention to enable 50 it to be understood; and Fig. 2 is a top or plan view of the base with the cylinder removed.

A represents a car of any usual or well-known construction suspended in an elevator-well or hoistway A' by a cable or rope a, 55 passed about the sheave a', located at the top of the building, and about a similar sheave a², mounted on a shaft a³, having bearings in uprights a⁴, secured to a cross-head a⁵, the opposite end of the rope being firmly secured, 60 as at a⁶, to a cross-bar a⁷ at the top of the building, the parts enumerated being of any usual or well-known construction. The cross-head a⁵ is connected, as herein shown, by two piston-rods b b', passed through suitable stuffing-boxes b² in the head of the closed cylinder b⁴, the said rods being connected at their other end in any usual or well-known manner, as by nuts b⁵, to the piston b⁶, provided 65 on its lower side with a depending lip or flange b⁷, fitted water-tight in the cylinder b⁴. The piston b⁶ above the lip b⁷, as herein shown, 70 is made of smaller diameter to leave an annular groove or space, in which is placed packing b⁸, normally kept compressed by the 75 follower-plate b⁹, secured to the top of the said piston, as by bolts b¹⁰. The cylinder b⁴ rests upon and is supported by a base c, provided 80 with legs c', preferably four in number, only two of which are shown in Fig. 1, the said cylinder being bolted or otherwise secured to the said base.

The base c is provided, in accordance with my invention, with a preferably central opening or port c², and with a second port c³, located at one side thereof. The base has secured to its under side by bolts, (not shown,) or in any other suitable manner, a valve-casing c⁴, herein shown as provided with tubular sleeves c⁵, having openings c⁶, which communicate with the ports of the valve-casing, the said sleeves forming a cylindrical passage for the piston-valves c⁷ c⁸ c⁹, mounted on a single valve-stem c¹⁰, provided at one end, as herein shown, with teeth to form a 90 rack-bar c¹¹, with which meshes a pinion c¹² on a shaft c¹³, provided with a pulley c¹⁴, with which is connected the usual shipper mechanism, herein shown as a shipper-rope c¹⁵, by operating which the said valves may be moved 95 to admit and discharge water into and from the cylinder b⁴, as will be described.

The valve-casing c⁴ is provided with a port d, constituting the water-inlet port, and with

the port d' , communicating with the central opening c^2 in the base, and with a port d^2 , forming the discharge-port for the said casting, and with a port d^3 , which registers with 5 the port c^3 in the base.

- 5 The base c has secured to it a stand-pipe d^5 , of any desired form in cross-section, communicating with the port or opening c^2 in the base and extended up into the cylinder 10 b^4 , so as to form a continuation of the said opening, the said stand-pipe being entirely concealed within the cylinder, and, as herein shown, extended into a recess on the under side of the cylinder-head d^6 . The stand-pipe 15 d^5 , at or near its upper end, is preferably provided with a series of ports or openings d^7 , through which the water from within the pipe may pass into the cylinder b^4 above the piston b^6 , and vice versa. As shown in Fig. 1, 20 the valves are on their centers and the car A is held suspended in the hoistway. If now it is desired to ascend, the shipper-rope will be operated in the direction indicated by arrow 18, so as to move the valve-stem c^{10} 25 and the valves attached thereto toward the left or in the direction indicated by arrow 20, so that the valve c^7 will uncover the port d' and the valve c^9 will open the port d^2 . In this case the water will enter by the port d^2 30 and flow through the port d^2 , stand-pipe d^5 , and passages d^7 into the cylinder b^4 above the piston, thus forcing the latter toward the bottom of the cylinder and elevating the car. The water in the cylinder b^4 below the piston 35 passes therefrom through the port c^8 , d^3 , and d^2 , preferably, to the discharge or waste-water tank. (Not shown.) When the elevator has reached the extent of its upward movement, the shipper-rope is moved in the opposite direction to bring the valves into their central 40 position, if it is desired to stop the elevator-car at its extreme upper position, and if it is desired to descend the said rope will be still further moved in the direction opposite to that indicated by arrow 18, so as to close 45 the inlet-port d by the valve c^7 and connect the port d' with the port d^3 , the exhaust-port d^2 being at such time closed. The piston b^6 will now be moved upward by the 50 weight of the car as the latter descends, and the water contained in the cylinder b^4 above the said piston will pass through the opening d^7 into the stand-pipe d^5 , thence through the ports d^7 d^3 c^3 into the cylinder below the piston, and when the valves are again moved to 55 cause the car to ascend the water in the cylinder b^4 below the piston will be forced, as described, through the ports c^8 d^3 and exhaust-port d^2 . The stand-pipe d^5 , being located within the cylinder b^4 , is removed from danger of derangement and damage, and the disagreeable noise occasioned by the water passing through the said pipe is reduced to 60

a minimum, for the reason that the cylinder, being full of water at all times, envelops 65 said pipe and prevents vibration of the same by the passage of the water through it.

By making the base c independent of the cylinder and concentric therewith the said base and the valve-casing attached thereto 70 may be turned into any desired position to make the proper connections with the operating parts—as, for instance, with the valve-operating mechanism, to secure perfect alignment of the valve-operating mechanism and 75 hoisting-ropes. This is especially advantageous where the space in which the mechanism is placed is limited in size and is irregular in outline, as by means of the movable base perfect alignment of the operating 80 parts is secured and the hoisting-ropes may be brought into correct working or operative position.

By making the piston movable on the stand-pipe within the cylinder I obtain an effective apparatus of simple construction, and, the piston being substantially light as compared with the cylinder, the friction is reduced to a minimum and a saving in power required is effected. 85

I claim—

1. In an elevator mechanism, the combination, with a closed cylinder and its piston operatively connected to the car, and a valve-casing provided with two ports communicating 95 with the said cylinder, of a pipe connected to one of said ports and extended into the cylinder through the piston, and having its opposite end communicating with the interior of the cylinder above the piston to form a liquid inlet and outlet for the cylinder at one side of its piston, and a valve to control said ports, substantially as described.

2. In an elevator mechanism, the combination, with a vertical cylinder and its piston 105 operatively connected to the car, of an independent base concentric with the cylinder, and a valve-casing secured to said base below said vertical cylinder, a valve in said casing, and mechanism to operate said valve, substantially as described.

3. In an elevator mechanism, the combination, with a cylinder and its piston operatively connected to the car, of a base provided with openings c^2 c^3 , communicating with the cylinder, and a pipe communicating with the opening c^2 and extended within the cylinder through the piston, substantially as described. 115

In testimony whereof I have signed my name to this specification in the presence of two subscribing witnesses.

CHARLES WHITTIER.
